DESIGN FOR A MEASURING SPOON

Charles J. Stuart, New Haven, Conn., assignor
to The Humason Manufacturing Company,
Forestville, Conn., a corporation of Connecticut

Application January 30, 1934, Serial No. 50,557

Term of patent 14 years

To all whom it may concern:

Be it known that I, CHARLES J. STUART, a subject of the King of Great Britain, and a resident of New Haven, in the county of New Haven State of Connecticut, have invented a new, original, and ornamental Design for a Measuring Spoon, of which the following is a specification, reference being had to the accompanying drawing forming part hereof.

Fig. 1 is a perspective view of a measuring spoon showing my new design;

Fig. 2 is a perspective view similar to Fig. 1 but showing the measuring spoon in inverted position with relation to the showing of Fig. 1; and

Fig. 3 is a longitudinal sectional view of a measuring spoon of my new design.

I claim:

The ornamental design for a measuring spoon as shown.

CHARLES J. STUART.
